SANITARY STERILIZER FOR BARBERS' STROPS

Abramo Di Filippo, Silver Spring, Md.

Application June 28, 1948, Serial No. 35,653

5 Claims. (Cl. 21—91)

1

This invention relates to improvements in sanitary sterilizers for barbers' strops.

An object of the invention is to provide an improved sanitary sterilizer for barbers' strops which will contain a strong disinfecting agent, and which will normally support the strop within the body of the sterilizer when the strop is not actually being used for sharpening a razor.

Another object of the invention is to provide an improved sanitary sterilizer for barbers' strops which will include a substantially tight body or casing in which a strong disinfecting agent will be disposed, and spring retracting means connected with a razor strop being disposed in said body or casing in close proximity to the disinfecting agent, being spaced therefrom by a perforated strop guiding and supporting plate.

A further object of the invention is to provide an improved retractile razor strop and sanitary sterilizer therefor, which will be adapted to be clamped upon the arm of a barber's chair or in any other place convenient to the barber while working.

A still further object of the invention is to provide an improved sanitary sterilizer for barbers' strops which will include a hollow body or casing in which a strong disinfecting agent will be disposed, together with a resilient type retractile means and a strop connected therewith for normally being inclosed within the body or casing when not actually in use, and a combined perforated guide and bearing plate for said strop which will serve the dual purpose of retaining the disinfecting agent in the body or casing and for furnishing a flat supporting and bearing surface for the strop.

Another object of the invention is to provide an improved sanitary sterilizer for barbers' strops which will be highly efficient in operation and relatively inexpensive to manufacture and produce.

Other objects will appear as the description proceeds.

In the accompanying drawings which form a part of this application,

Figure 1 is a perspective view of the improved sanitary sterilizer for a barber's strop;

Figure 2 is a plan view of the improved sanitary sterilizer for a barber's strop with the top of the body or casing removed;

Figure 3 is a longitudinal vertical sectional view through the improved sanitary sterilizer for a barber's strop;

Figure 4 is a sectional view taken on the line 4—4 of Figure 3, and

Figure 5 is a sectional view taken on the line 5—5 of Figure 3.

Like characters of reference are used throughout the following specification and the accompanying drawings to designate corresponding parts.

2

In carrying out the invention, there is shown and provided an improved sanitary sterilizer for a barber's strop including an elongated relatively narrow body or casing generally designated by the reference numeral 1, having a bottom 2, opposite sides 3 and 4, and opposite ends 5 and 6. The body or casing 1 is also formed with a vertical partition 7 adjacent one end thereof, and a second vertical partition 8 approximately midway between the partition 7 and the further end 6 of the body or casing 1, all of which construction is preferably made of integral formation, and preferably made from plastic or some other suitable light waterproof material.

15 A top or cover plate 9 is provided, the same being of a length to completely cover the full length and width of the body or casing 1, and will be detachably secured in position upon the body or casing 1 by means of the screws 10.

The vertical partition 7 extends the full depth of the body or casing 1, and is formed with a transversely extending elongated slot 11 in its upper surface for purposes hereinafter more fully described, while the partition 8 extends upwardly to a point somewhat below the upper edge of the body or casing 1.

20 A U-shaped metal bracket 12 is adapted to be supported by means of the screws bolts 13 in the compartment 14 formed at the end of the body or casing 1 between the partition 7 and the adjacent end 5 of said body or casing 1, and the sides 15 and 16 of the bracket 12 extend longitudinally of the body or casing 1 and in spaced relation from the opposite sides 2 and 3 thereof, forming compartments 17 and 18.

25 A shaft 19 is rotatably mounted between the sides 15 and 16 of the bracket 12, extending therethrough and having its opposite ends extending to points adjacent the sides 2 and 3 of the casing 1.

30 Flat spiral springs 20 and 21 are secured at one end of each spring in notches 22 and 23 formed in the end 5 of the body or casing 1 by means of the screws 24, and are disposed within the compartments 17 and 18, with their opposite 35 ends being attached and fixed to the ends of the shaft 19 by means of the screws 25, said springs 20 and 21 being normally in their expanded position.

An elongated fabric web 26 is attached at one 40 end to the shaft 19 by means of the screws 27, and is wound about the shaft, with its free end extending through the slot 11 in the partition 7, and terminating in the cross member 28 attached thereto. An eye 29 is attached to the cross member 28 and is connected with the eye 30 formed on the inner end of a barber's strop 31, which is of a length to extend to and beyond the far end of the body or casing 1, extending through the slot 32 in the upper edge of the end 6, whereby the strop 31 may be pulled outwardly from the body or casing 1 to its extended position and

turned to present either side of the strop for stropping a razor (not shown), said strop 31 when being pulled outwardly causing the fabric web 26 to be unrolled from the shaft 19 and the spiral springs 20 and 21 to contract or tighten up, thus providing the means for retracting the strop 31 to its position within the body or casing 1 when it is released.

Blocks or pads of absorbent material 33 and 34 are disposed within the body or casing 1 at either side of the partition 8, and are adapted to be saturated or impregnated with any desired disinfecting fluid or agent which will be of a potency of from 95% to 100% in solution form.

An inverted U-shape guide plate 35 having depending supporting ends 36 and 37 is formed with a plurality of perforations 38, and is adapted to be positioned over the blocks or pads 33 and 34, with the lower ends of the opposite ends 36 and 37 resting upon the upper surface of the body or casing bottom 2, and in direct contact with the upper surfaces of said blocks or pads 36 and 37. The guide plate 35 will be held in fixed position by means of the screws 39 which extend through it and into the upper surface of the partition 8. The guide plate 35 will be formed with upwardly extending side guide flanges 40 and 41 extending the full horizontal or longitudinal length of the plate, and the width between said flanges 40 and 41 being the width of the usual razor strop 31, whereby the side edges of the strop 31 will engage the same to be guided thereby when the strop 31 is withdrawn from the body or casing 1, or is retracted into the body or casing 1. The opposite ends of the horizontal or longitudinal portion of the guide plate 35 will be rounded as at 42 and 43 to provide bearing surfaces for the strop 31 as it is moved into and out of the casing or body 1. It will be seen and understood that the strop 31 will be supported directly upon the upper surface of the guide plate 35 with its edges in contact with the guide flanges 40 and 41, which also serve to strengthen and reinforce the guide plate 35, making the same substantially rigid. An attaching bracket 44 will be disposed on the casing 1 for attaching the sterilizer to a support.

Inasmuch as barbers seldom ever clean their strops or razors, it is apparent that when a customer's face is cut, possible germs may be picked up by the razor and transferred to the strop to infect another customer or many customers. However, with the strop being thoroughly sterilized by the disinfecting agent every time it is used, this serious spreading of infection will be rendered impossible.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention what I claim as new and desire to secure by Letters Patent of the United States is:

1. A sanitary sterilizer for barbers' strops including a casing having a bottom, side and end walls, transversely extending spaced partitions in said casing forming three longitudinally aligned compartments, a shaft rotatably mounted transversely in one of said compartments, a web wound upon said shaft, resilient means connected with said shaft for holding said web wound thereon in retracted position, disinfecting agent im-

pregnated blocks disposed in the other two compartments, a perforated guide plate having upwardly extending guide flanges formed along its opposite edges disposed over said blocks and secured to the upper edge of one of said partitions, a strop attached to said web supported in normal position upon the upper surface of said guide plate with its edges contacting the guide flanges on said plate extending the full length of said guide plate and beyond the end of said casing, a detachable cover for said casing, and said strop being pulled from said casing against the action of said resilient means when the strop is to be used and said resilient means automatically retracting the strop into the casing after the strop has been used.

2. A sanitary sterilizer for barbers' strops including a casing having a bottom, side and end walls, transversely extending spaced partitions in said casing forming three longitudinally aligned compartments, one of said partitions and the remote end of said casing being formed with transversely extending slots in their upper edges, a U-shape bearing bracket secured in an end compartment in said casing, a shaft rotatably mounted in said bracket, a web wound upon said shaft, spiral tensioning springs connected between the adjacent end of said casing and the opposite ends of said shaft for normally and resiliently holding said web wound upon said shaft, disinfecting agent impregnated blocks disposed in the other two compartments, a perforated guide plate formed with upwardly extending guide flanges along its opposite sides disposed over said blocks and secured to the upper edge of one of said partitions, a strop attached to the outer end of said web supported in normal position upon the upper surface of said perforated guide plate with its edges contacting and guided by the guide flanges on said plate extending the full length of said guide plate and beyond the end of said casing, a detachable cover for said casing, and said strop being pulled from said casing against the action of said spiral springs to unwind said web from said shaft when the strop is to be used and said spiral springs automatically retracting said web and strop after the strop has been used.

3. The subject matter as claimed in claim 2, and the sides of said U-shape bracket extending in spaced relation with the sides of said casing to form parallel compartments in which said spiral springs will be housed.

4. The subject matter as claimed in claim 2, the sides of said U-shape bracket extending in parallel spaced relation with the sides of said casing to form parallel compartments in which said spiral springs will be housed, and means connected with the outer end of said web for limiting the amount said web may be wound upon said shaft.

5. The subject matter as claimed in claim 2, the sides of said U-shape bracket extending in parallel spaced relation with the sides of said casing to form parallel compartments in which said spiral springs will be housed, means connected with the outer end of said web for limiting the amount said web may be wound upon said shaft, and said perforated guide plate having rounded bearing surfaces at its opposite ends terminating in depending parallel supporting legs adapted to rest upon the bottom of said casing.
